(57) **CLAIM**

The ornamental design of a container, as shown and described.

DESCRIPTION

FIG. 1 is a first perspective view of a container in accordance with the present invention;

FIG. 2 is a front view thereof;

FIG. 3 is a back view thereof;

FIG. 4 is top view thereof;

FIG. 5 is a bottom view thereof; and,

FIG. 6 is a right side view thereof, the left side view being a mirror image.

The broken lines showing the mouth of the container in FIGS. 1-4 and 6 and portions of the bottom of the container in FIG. 5 illustrate portions of the container that form no part of the claimed design.

More generally, the invention pertains to an ornamental design for an article of manufacture. The article is not limited to the scale shown herein. As indicated by the title, the article of manufacture to which ornamental design has been applied is a container, such as food packaging.
